UNITED STATES PATENT OFFICE.

FRANCIS A. COFFIN, OF INDIANAPOLIS, INDIANA.

DESIGN FOR A WRITING-TABLE.

SPECIFICATION forming part of Design No. 19,293, dated September 3, 1889.

Application filed July 27, 1889. Serial No. 318,973. Term of patent 7 years.

To all whom it may concern:

Be it known that I, FRANCIS A. COFFIN, of Indianapolis, county of Marion, and State of Indiana, have invented a certain new and original Design for Writing-Tables; and I do hereby declare that the following is a full, clear, and exact description thereof, reference being had to the accompanying drawings, in which like letters refer to like parts.

10 My invention consists in a new and original design for writing-tables, and will be understood from the following description.

In the plate accompanying this specification the figure shows a perspective view of my 15 table with one of the cupboard-doors open.

The top of the table is of octagonal shape, having molded edges with rosette ornaments between the moldings, as shown. This top is supported by four rectangular pedestals set in shape of a four-armed cross, and the front corners of the pedestals are finished with molded side pieces or brackets tapering from near the top toward the bottom. The legs are squared at the top, molded below, and

thence tapered toward the bottom, and brackets are placed between the squared tops of the legs and at the sides, as shown.

The design herein shown permits the use of the table by four persons at one time, the angular spaces between the pedestals affording room for the legs of the sitter, and each will have a cabinet at his right hand for his own private papers.

What I claim as my invention is the following:

A design for writing-tables, consisting of an octagonal top with molded edges supported upon four pedestals in the shape of a cross, each pedestal being of a rectangular shape, the whole supported upon tapered legs, substantially as shown and described.

In witness whereof I have hereunto set my hand this 8th day of July, 1889.

FRANCIS A. COFFIN.
